UNITED STATES PATENT OFFICE.

SHELDON F. BURLINGAME AND CARL E. BURLINGAME, OF WORCESTER,
MASSACHUSETTS.

GAS-ENGINE.

SPECIFICATION forming part of Letters Patent No. 780,635, dated January 24, 1905.

Application filed December 18, 1903. Serial No. 185,670.

To all whom it may concern:

Be it known that we, SHELDON F. BURLINGAME and CARL E. BURLINGAME, citizens of the United States, residing at Worcester, in the county of Worcester and State of Massachusetts, have invented a new and useful Gas-Engine, of which the following is a specification.

This invention relates to an attachment for starting gas-engines into operation.

The especial object of this invention is to provide an attachment for starting gas-engines by the use of explosive cartridges, said attachment being so constructed that the paper wads of the explosive-cartridges will be caught at the end of the explosion-tube in such position that they will be burned up by the successive charges of burning gases after the engine has been started.

To these ends this invention consists of the starting attachment for gas-engines and of the combinations of parts therewith, as hereinafter described, and more particularly pointed out in the claim at the end of this specification.

In the accompanying drawings, Figure 1 is a sectional view of sufficient parts of a gas-engine to illustrate the application of our invention thereto. Fig. 2 is an enlarged sectional view of the firing-tube in which the cartridge is exploded to start the engine. Fig. 3 is a similar view showing how the paper wad of the cartridge is caught at the end of the explosion-tube when the cartridge is exploded, and Fig. 4 is a similar view showing the manner in which the paper wad is consumed or burned up.

One of the most serious difficulties incident to operating gas-engines is to provide means for securing the starting of the gas-engine into operation. In the use of the ordinary gas-engines which are now employed the main shafts of the engines have to be given one or two turns by hand before the engine will start. To overcome this objection, it has already been proposed to utilize the pressure from the explosion of a cartridge or shell for the purpose of starting a gas-engine. In the actual use of explosive cartridges for starting gas-engines we have experienced considerable

difficulty by reason of the paper or pasteboard wad from the shell being blown into the cylinder of the gas-engine and afterward chocking up the valves or preventing the valves from closing. To overcome this objection, in an engine-starting attachment constructed according to this invention we employ an explosion-tube which we have extended into the engine-cylinder, so that the end of the tube will be exposed to the heat of the successive explosions of gas after the engine has been started. The lower end of the explosion-tube is partly closed, so that when a cartridge is fired the paper wad will lodge in the end of the explosion-tube which extends to the inside of the engine-cylinder, and we have found this arrangement to be one of considerable practical importance, as by adopting this construction the paper wad of the cartridge will not be permitted to enter the engine-cylinder and will be burned up or consumed from the heat of the successive charges of burning gas during the operation of the engine.

Referring to the drawings for a detail description of a starting attachment for gas-engines constructed according to our invention, as shown in Fig. 1, C designates an ordinary engine-cylinder, mounted in which is the piston P. Secured on the end of the cylinder C is the cylinder-head H, and tapped into the cylinder-head H is a supply-pipe S. These parts may be of any ordinary or approved construction and need not be herein described at length.

Secured in the cylinder-head H is an explosion-tube 10. The lower end of the explosion-tube extends down to the inside of the cylinder, and the explosion-tube is secured in place by flanges 11, which are fastened by bolts 12. Threaded onto the upper end of the explosion-tube 10 is a removable breech-block 13, having a spring firing-pin 14 mounted therein and held from turning by a pin 15. An ordinary cartridge 17—such, for example, as employed in shotguns or similar firearms—may be dropped into the upper end of the explosion-tube 10. The cartridge 17 is provided with a percussion-cap or primer 18, and the cartridge 17 may be loaded with any ordinary

explosive which may be held in place by the paper wad 19. In practice we have secured the best results by using a smokeless or brown nitro gunpowder, and we prefer to use this 5 smokeless gunpowder, as we have found that the same will not tend to smoke up or dirty the inside of the engine-cylinder.

In the use of an attachment as thus constructed the breech-block is unscrewed, a cartridge is put in position, the breech-block is replaced, and the main shaft of the engine is turned so that the piston stands in position to commence its downstroke. The cartridge is then exploded by the firing-pin, as illustrated 15 in Fig. 3, the wad being caught and retained in the end of the explosion-tube. The explosion of the cartridge will generate sufficient pressure to start the engine into operation to perform the successive functions of drawing 20 in, compressing, and exploding subsequent charges of explosive mixture. The explosion of these successive charges of gas will cause the paper wad to be burned up and consumed, as illustrated in Fig. 4.

25 We are aware that changes may be made in practicing our invention by those who are skilled in the art without departing from the

scope thereof as expressed in the claim. We do not wish, therefore, to be limited to the particular construction we have herein shown 30 and described; but

What we do claim, and desire to secure by Letters Patent of the United States, is—

The combination of a gas-engine cylinder, and an attachment for starting the engine by the explosion of a cartridge consisting of an explosion-tube adapted to receive a cartridge or shell at one end, with its other end extended into the engine-cylinder in position to be exposed to the successive charges of burning 35 gas, said inwardly-projecting end being closed except for perforations of smaller diameter than the bore of the tube, whereby the wad of the cartridge fired in the explosion-tube 40 will be lodged and consumed in the explosion-tube without passing into the engine-cylinder. 45

In testimony whereof we have hereunto set our hands in the presence of two subscribing witnesses.

SHELDON F. BURLINGAME.
